UNITED STATES PATENT OFFICE.

WARREN E. WARNER, OF ROCHESTER, NEW YORK.

DESIGN FOR A FOOT-PLATE FOR BICYCLE-PEDALS.

SPECIFICATION forming part of Design No. 26,178, dated October 13, 1896.

Application filed August 26, 1896. Serial No. 604,034. Term of patent 7 years.

To all whom it may concern:

Be it known that I, WARREN E. WARNER, a citizen of the United States, residing at Rochester, in the county of Monroe and State 5 of New York, have invented and produced a new and original Design for a Foot-Plate for Bicycle-Pedals, of which the following is a specification, reference being had to the accompanying drawings, showing a part thereof.

10 My design relates to the form and configuration of a foot-plate for "rat-trap" pedals; and it consists, essentially, in forming the parallel sides with central longitudinal depressions or corrugations and the integral 15 outer end or face of the pedal in the general form of a circle having upwardly and downwardly extending rounded points and a concentric perforation. At each side of the circular center the end narrows into curved 20 bands substantially equal in width to the corrugations of the sides.

My invention will be better understood by reference to the accompanying drawings, in which the same numerals of reference refer 25 to corresponding parts in all the views.

Figure I is a top plan view of a pedal foot-plate, showing my design. Fig. II is a side elevation thereof. Fig. III is an elevation of the outer end. Fig. IV is an elevation of the 30 inner end.

11 are the sides, connected to the substantially circular end 2 by the curved and narrower corner portions 3 3. The sides are similar and parallel and have each a central 35 longitudinal depressed portion or corrugation

4 substantially equal in width to the corner portion 3. This depressed portion is conspicuous in Figs. III and IV and is preferably decorated with perforations, as shown in Fig. II. The upper and lower edges 5 5 of 40 the side pieces are bent outwardly with a double bend, being formed on the extreme edge into teeth 6 6, as here shown. The inner ends 7 7 of the sides are substantially square, being slightly notched at 8. The 45 outer end or face 2 of the foot-plate, which is the more conspicuous when the pedal is on the bicycle, is substantially flat, its basic form being a circle, of which 9 9 9 are the arcs. It is extended above and below into rounded 50 points 10 10. The end is solid, except for a central circular perforation 11, with which the arcs 9 9 9 are concentric, and is decorated with a corrugation 12 12 12, parallel to the outline of the end. Respectively outside 55 and inside of the corrugation are the plane bands 13 13 13 and 14.

Having thus described my invention, what I claim is—

The design for a foot-plate for bicycle- 60 pedals, substantially as shown and described.

In witness whereof I have hereunto set my hand, in the presence of two attesting witnesses, at Rochester, in the county of Monroe, in the State of New York, this 21st day of 65 August, 1896.

WARREN E. WARNER.
